UNITED STATES PATENT OFFICE

104,832

DESIGN FOR A THERMOMETER

John L. Chaney and Ralph C. Wappner, Springfield, Ohio

Application March 17, 1937, Serial No. 68,243

Term of patent 3½ years

To all whom it may concern:

Be it known that we, John L. Chaney and Ralph C. Wappner, citizens of the United States, residing at Springfield, in the county of Clark and State of Ohio, have invented a new, original and ornamental Design for a Thermometer, of which the following is a specification, reference being had to the accompanying drawing, forming a part thereof.

In the drawing:

Figure 1 is a front elevation of a thermometer showing our new design;

Figure 2 is a rear elevation thereof; and

Figure 3 is a top plan view thereof.

We claim:

The ornamental design for a Thermometer substantially as shown.

JOHN L. CHANEY.
RALPH C. WAPPNER.
